LOOM DROP-BOX CONNECTION

Application filed January 15, 1929. Serial No. 332,591.

This invention relates to improvements in connections for drop box looms and it is the general object of the invention to provide a connection wherein the shifting shuttle boxes may move slightly relatively to their lifter rod for the purpose of relieving the latter from strains.

In the usual drop box loom the shifting shuttle boxes are ordinarily fastened rigidly to the upper end of the lifter rod. I have found that this construction requires a rather large and strong rod to resist the twisting which occasionally takes place between the boxes and the controlling connections thereof. It is an important object of my present invention to provide a connection between the box rod and the boxes which will permit the shuttle boxes to have a limited angular movement with respect to the said rod, but will give the boxes a positive controlling movement.

It is a further object of my present invention to provide an improved form of connection between the shuttle boxes and their lifter rod in the form of a nut non-circular in outline and held in a pocket suitably provided on the shuttle boxes.

With these and other objects in view which will appear as the description proceeds my invention resides in the combination and arrangement of parts hereinafter described and set forth in the claims.

In the accompanying drawings wherein a convenient embodiment of my invention is set forth,

Fig. 1 is a front elevation of one end of a loom having my invention applied thereto,

Fig. 2 is a section taken on line 2—2 of Fig. 1 on an enlarged scale, and

Fig. 3 is a vertical section on line 3—3 of Fig. 2.

As shown in Fig. 1 I have provided a loomside 10 and breast beam 11 together with a lay 12 which supports the usual reed, not shown, and hand rail 14. The lay is provided with an inner box guide 15 and a second outer box guide 16 held to the lay in any approved manner as by bolts 17. The shuttle boxes are arranged in a gang 50 and have tongues 18 and 19 which are re-

ceived by grooves 20 and 21, respectively, formed in the guides 15 and 16, respectively. Each of the cells of the shuttle box may be provided with a binder 22 having a binder spring 23.

The lower portion of the loom is provided with a rocker shaft 24 on which is mounted a rocker iron or foot 25 supporting the picker stick 26. An upturned horn 27 on the rocker iron has extending therethrough a lifter rod 28, the lower end of which is connected by means of an adjustable element 29 to a link 30. The element 29 is provided with a stud 31 extending through the link 30 and said element is positioned vertically with respect to the lifter rod 28 by means of nuts 32. The link 30 is raised in any approved manner as by a portion of the box motion designated generally at 33 and by means of said link the lifter rod is given a plurality of positions, being in highest position shown in Fig. 1 with the lowest box opposite the race of the lay.

The matter thus far described is of common construction and forms no part of my present invention, the lifter rod being moved vertically to place the proper shuttle in action by mechanism not shown but well understood. The lay moves back and forth with respect to the breast beam and carries therewith the connector or lifter rod 28.

My invention relates more particularly to the manner of connecting the upper end of the lifter rod to the multicell shuttle box designated generally at B. The gang of shuttle boxes has secured to the under side thereof a strap 40 by means of rivets 41, said strap having an offset portion 42 which defines with the adjacent bottom 43 of the lowest shuttle box a pocket 44 which as shown in Fig. 2 is of rectangular form.

I provide the upper end of the rod 28 with screw threads 45 which are preferably of slightly less diameter than the diameter of the rod thereby defining a shoulder 46. There is threaded onto the screw portion 45 of the rod a nut 47 which is non-circular in form and so proportioned as to workably engage the side walls 48 of the strap which defines the pocket 44. The threaded exten-

sion 45 of the rod is of less length than the vertical dimension of the nut as clearly shown in Fig. 3.

A further feature of my invention relates 5 to the formation of the nut to permit the same to move through a slight angular motion within the pocket. The bottom 43 of the lower shuttle box and the offset portion 42 of the strap are substantially parallel but 10 I provide the nut with upper and lower convex surfaces 50 and 51, respectively. The width of the nut is also slightly less than the distance between the vertical walls 48 so that a slight angular movement of the shuttle box is permissible with respect to the nut 47 without impairing the vertical positive- 15 ness of the lifter rod. It is preferable to have the rod 28 so located that it is substantially under the center of gravity of boxes so that the latter will be moved evenly when the lifter rod 28 is elevated or lowered.

In assembling my improved construction the nut 47 is inserted in the pocket after which the upper end of the rod is extended 20 through an opening 52 in the lower offset part 42 of the strap. The opening 52 is somewhat larger than the diameter of the rod 28. Said rod is then turned tightly into the nut, rotation of the latter being prevented by the side walls 28. The shoulder 46 is forced against the under surface of the nut so that the nut and rod in effect become a unified structure.

In operation the lifter rod 28 may be 25 raised as previously stated, lifting motion being communicated from the rod through the upper convex surface 50 to the bottom 43 of the lower shuttle box. In a similar manner lowering of the box may be accomplished by the rod by contact between the lower surface 51 of the nut and the offset part 42. As a matter of fact, however, the down motion is usually due to gravity and the lifter rod acts to limit downward movement so that the correct shuttle box may be 30 positively aligned with the lay.

If the shuttle boxes should be slightly out of alignment with the race plate the box rod 28 will not be subjected to any strain tending to bend the same due to the fact that the connection between the nut 47 and the shuttle box parts will permit said nut to have a slight angular motion with respect to the shuttle boxes. Some loom fixers, for instance, consider that the shuttle box floor 35 should tip down slightly so as to give the shuttle a downward motion tending to cause the same to fly closely to the race plate. Due to this and to other causes the shuttle boxes 40 may not move in a direction strictly parallel to the motion of the box rod, but as previously stated the latter will be relieved from twisting and may therefore be made lighter and of less diameter than has been 45 the practice heretofore.

From the foregoing it will be seen that I have provided a very simple connection between the shuttle boxes and the box lifter rod which permits a slight angular movement of the boxes in all directions with respect to their lifter rod to the end that the latter may be relieved of twisting strains. Furthermore, it will be seen that the pocket which receives the nut is so proportioned as to resist unlimited angular movement of the nut around the axis of the rod 28. It will be seen more specifically that the nut is provided with convex upper and lower surfaces and that the shoulder 46 acts to keep the upper end of the threaded portion 45 of the rod below the top convex surface 50.

Having thus described my invention it will be seen that changes and modifications may be made therein by those skilled in the art without departing from the spirit and scope of the invention and I do not wish to be limited to the details herein disclosed, but what I claim is:

1. In a loom having a shifting shuttle box and having also a box lifter rod to give the shuttle box a plurality of positions relatively to the lay, means defining a non-circular pocket on the under side of the shuttle box, and a singular non-circular element secured to the box lifter rod and located loosely within the pocket and positioned to engage the side walls of the pocket, the upper surface of the element being convex and being the sole supporting connection between the lifter rod and the shuttle box.

2. In a loom having a shuttle box with a substantially flat bottom and a box lifter rod to move the shuttle box to a plurality of positions, means defining a convex surface carried by the upper end of the rod to engage the bottom of the shuttle box and being the sole support for the latter, and a loose connection between the lifter rod and the shuttle box permitting limited angular movement of the shuttle box in all directions with respect to the lifter rod.

3. In a loom having a shuttle box with a substantially flat bottom and a box lifter rod to move the shuttle box to a plurality of positions, a non-circular nut mounted on the upper end of the lifter rod and having a convex surface to engage the flat bottom of the shuttle box, and means defining a loose connection between the shuttle box and the lifter rod, whereby a slight angular rolling movement of the shuttle box over the upper surface of the nut may take place.

4. In a loom having a shuttle box with a substantially flat bottom and a box lifter rod to move the shuttle box to a plurality of positions, means defining a convex surface on the upper end of the lifter rod to have rolling contact with the bottom of the shuttle box, and means to restrict the angu- 130

lar movement of the shuttle box with respect to the rod.

5. In a loom having a shuttle box movable between a pair of spaced box guides, a box lifter rod movable to a plurality of vertical 5 positions, means on said rod presenting a rounded upper surface located substantially midway between the guides, and additional means on the shuttle box presenting a downwardly facing surface to engage the rounded 10 surface, the weight of the shuttle box being transmitted through said surfaces to the lifter rod.

6. In a loom having a shuttle box movable between a pair of spaced box guides, 15 a box lifter rod movable to a plurality of vertical positions, means on said rod presenting a single convex upper surface located substantially midway between the guides, and additional means on the shuttle box presenting a downwardly facing surface to engage the single convex surface, the weight 20 of the shuttle box being transmitted through said surfaces to the lifter rod.

7. In a loom having a shuttle box movable 25 between a pair of spaced box guides, a box lifter rod movable to a plurality of vertical positions, means on the bottom of the shuttle box defining a pocket, means on the top 30 of the lifter rod presenting an upwardly facing rounded surface located in the socket and engaging the top of the pocket to afford the sole means of support for the shuttle box, said last named means being movable with a 35 limited freedom in the pocket and the shuttle box and lifter rod being capable of slight angular movement.

8. In a loom having a pair of horizontally 40 spaced vertical box guides, a shuttle box located between and movable vertically along the guides, a box lifter rod located between the guides and capable of assuming a plurality of vertical positions relatively to the guides, and a single pivotal connection between the lifter rod and shuttle box supporting the weight of the shuttle box, the 45 connection being so formed that the shuttle box is capable of slight angular motion relatively to the lifter rod in two vertical planes, one of said planes being transverse of and the other plane being substantially parallel to the horizontal axis of the shuttle box.

In testimony whereof I have hereunto 50 affixed my signature.

55 CARL J. LINDEGREN.
